UNITED STATES PATENT OFFICE.

WILLY H. LAU, OF CHICAGO, ILLINOIS.

ELECTRIC AND COMBINED ELECTRIC AND GAS CHANDELIER OR BRACKET.

SPECIFICATION forming part of Letters Patent No. 621,104, dated March 14, 1899.

Application filed June 6, 1898. Serial No. 682,655. (No model.)

To all whom it may concern:

Be it known that I, WILLY H. LAU, a citizen of the United States of America, residing at Chicago, in the county of Cook and State 5 of Illinois, have invented a certain new and useful Electric and Combined Electric and Gas Chandelier or Bracket, of which the following is a specification.

My invention relates to improvements in 10 electric and combined electric and gas chandeliers and brackets; and the object of my invention is to obtain an electric and also a combined electric and gas chandelier and bracket in which the ordinary insulating- 15 joint heretofore used in such chandeliers and brackets will not be required for the gas-pipe, but in place thereof a loop (forming a cap and joint to the gas-pipe) or a common stiff joint will be used to obtain a combined electric 20 and gas chandelier or bracket which can be used without causing combustion from the electric conductor or fixture used in connection therewith, and to obtain an electric and a combined electric and gas chandelier and bracket in the use of which no grounding of 25 the electric conductors will be liable to occur.

A further object of the invention is to obtain an electric and a combined electric and gas chandelier and bracket which will be 30 slightly in appearance, readily assembled, and durable.

In the drawings accompanying and forming a part hereof the manner in which the objects sought is well shown in the mechanisms illustrated, in which drawings—

Figure 1 is a sectional elevation of a combined electric and gas chandelier embodying the invention; Fig. 2, a bottom plan view of the chandelier illustrated in Fig. 1; Fig. 3, a 40 bottom plan view of a modification of a portion of the chandelier illustrated in Figs. 1 and 2, showing a chandelier arranged for electric connections only. Fig. 4 is a detail view of the combined gas and electric distributor, forming an element in the apparatus embodying the invention. Fig. 5 is a plan view of the combined electric and gas distributor illustrated in detail in Fig. 4, and Fig. 6 is a sectional elevation of a stiff-joint 45 cap for an electric chandelier or bracket.

A reference-letter applied to designate a given part is used to indicate such part

throughout the several figures of the drawings wherever the same appears.

A is a stiff joint in common use in gas-fittings.

B is an ordinary vertical gas-pipe for a chandelier secured in stiff joint A by means of external screw-threads thereon, fitting corresponding internal screw-threads in stiff 60 joint A.

C is an ordinary gas-distributer.

D is an ordinary casing in common use in gas-pipe fittings.

E is an ordinary canopy.

F is a sleeve on pipe B, of non-electric conducting material, forming an insulating-sleeve interposed between the casing D and stiff joint A.

G is a pipe of non-electric conducting ma- 70 terial forming an insulating-covering to the gas-pipe B.

H is an electric distributor comprising the central body part h of non-electric conducting material, and the metal rings h' h', secured together and to the part h by the bolts h² h³, having nuts h³ h³, respectively, thereon. Body part h of electric distributor H may be composed of two pieces h⁴ h⁴, as illustrated in 75 Fig. 4. The upper ring h' has lugs or projections h⁵ h⁵ on the peripheral edge thereof, and the lower ring h' has short projections h⁶ h⁶ on the peripheral edge thereof, arranged to engage with projections h⁵ h⁵, respectively.

I I are holes through the central body part 85 h of non-electric conducting material, through which the ordinary gas-pipes J J extend to connect with the gas-distributer C in the ordinary way, as by external screw-threads on the gas-pipe engaging with corresponding internal screw-threads in the hole in the gas-distributer. The gas-pipes J J thus serve to hold the electric distributor H in place surrounding the gas-distributer C. When no gas-pipes J J extend through the electric distributor H, or an insufficient number to hold it in place extend therethrough, bolts or screws J' J', as in Fig. 3, are used to secure such electric distributor to the gas-distributer. When the part h of electric distributor H is 90 made in two parts, as h⁴ h⁴, Fig. 4, the hole I is obtained by having the grooves i i made in 95 the respective parts h⁴ h⁴.

K is a sleeve of non-electric conducting ma-

terial on gas-pipe J. The hole I at the end thereof adjacent to the periphery of the electric distributer H is made of the same diameter as is the sleeve K, and such sleeve K enters into such hole I to avoid the necessity of close fittings in assembling the several parts of the apparatus.

L is a metal band having holes l l l therein, through which holes the sleeves K K pass, respectively, thereby insulating such band, as well as supporting it in place.

M is the upper half of a globe, which rests on its lower peripheral edge on band L.

N N are internally-screw-threaded holes in projections h⁵ h⁵, respectively, into which holes the hollow electric arms or brackets O O respectively fit, and by which such brackets or arms are supported. Arms or brackets O O have external screw-threads O' O' thereon, fitting internal screw-threads N' N'.

P P are holes or grooves through electric body part h of electric distributer H, through which holes the electric conductors Q pass to enter the arms or brackets O O, respectively.

When part h of the electric distributer H is made of two pieces, as h⁴ h⁴, Fig. 4, the holes or grooves P P are obtained by making the grooves p p in such parts h⁴ h⁴.

To insert electric conductor Q in place, hole or slot q having been provided therefor, such conductor is placed within the casing D at the upper end of such casing and covered by the canopy E and extended downward through the casing between it and the insulating tube 35 or material G to underneath the combined electric and gas distributer H C. From thence the conductor Q is put through holes P P into the arms or brackets O O and to the electric lamps O² O² in the ordinary way.

R is a bracket, which may be of metal, secured to the electric distributer H by the bolts h² h², and S is a bolt extending through bracket R and secured in an adjusted position therein, as by external screw-threads S' S' thereon, fitting into corresponding internal screw-threads R' R' in bracket R.

M' is the lower half of a globe surrounding the combined electric and gas distributer H C, and is held in place against band L by bolt S. Access can be obtained to electric conductor Q at any time by removing bolt S and lower half 50 M' of the globe.

Where an electric chandelier or bracket only is to be secured to and held in place by a gas-pipe, the gas-pipe can be closed and the chandelier or bracket suspended from the loop T, forming a combined cap and joint. (Illustrated in Fig. 6.) Loop T comprises the internally screw-threaded part t, fitting over 55 the gas-pipe in the same manner as stiff joint A is fitted thereover, and secured thereto by the internal screw-threads therein engaging with external screw-threads on the gas-pipe, the plate t' closing the opening in the gas-pipe, and screw-threaded part t', to which the pipe 60 U is secured, as to a stiff joint, by external screw-threads u thereon engaging with cor-

responding internal screw-threads t³ t³, and the hollow body part having hole V therein below plate t, through which hole the electric conductor is inserted to extend through pipe U.

W is a pipe or tube of non-electric conducting material inserted in pipe U to insulate the conductor Q from such pipe.

Y is a plug in gas-distributer C.

The combined electric and gas distributer H C can be secured to the lower end of the pipe U, Fig. 6, (which may be ordinary gas-pipe,) in the same manner in which such combined electric and gas distributer is secured to the lower end of pipe B—that is, by having external screw-threads thereon fitting into corresponding internal screw-threads in a hole in such combined electric and gas distributer. In such case the electric arms or brackets O O may be of the same size as hereinbefore described and secured in place to the combined electric and gas distributer H C, as described, and the screws J' J', Fig. 3, 80 be substituted for the gas brackets or arms J J, Fig. 2. The conductor Q will then pass entirely through the pipe U and the combined electric and gas distributer H C, coming out of such combined electric and gas distributer 85 at the bottom thereof, and from thence through holes P P and into the electric brackets or arms O O, as hereinbefore described.

It will be evident that by having a hole on the under side of the combined electric and gas distributer H C an additional pipe B or an additional pipe U can be suspended to the combined electric and gas distributer, and so more than one series of gas and electric arms or brackets (or electric arms only) obtained. 90 Where pipe U is to be suspended to the combined electric and gas distributer, an additional stiff joint A and joint T is interposed between the combined electric and gas distributer and such pipe U.

X X' are insulating-rings to canopy E.

To assemble the several parts embodying this invention, the pipe B is secured to stiff joint A, insulating tube or pipe G is placed over pipe B, insulating ring or sleeve F is put in place, casing D is placed over the pipe B and tube G, insulating ring X, canopy E, and insulating-ring X' placed over the casing D to be slid up into place after the conductor Q has been inserted through slot or hole q and brought down through the casing D and the upper half of globe M M' put in position. The combined electric and gas distributer H C (to which the gas arms or brackets J J, electric arms or brackets O O, and band L may have been previously attached) is secured in place at the lower end of the pipe B and the conductor Q electrically connected (through the holes P P and arms or brackets O O) with the electric lamps. The lower half of the globe M M' is then put in place and secured by the bolt S.

Before putting the lower half of globe M M' in place the lower hole through the com-

bined electric and gas distributer H C is stopped, as by the plug Y.

Having thus described the invention, what I claim as new, and desire to secure by Letters Patent, is—

1. In a combined electric and gas chandelier and bracket, the combination with an ordinary vertical pipe, gas-distributer and gas-bracket arms, of an electric distributer concentric with the gas-distributer and comprising a ring of non-electric conducting material surrounding the gas-distributer, through which ring the gas-bracket arms extend thereby supporting it in place, electric bracket-arms secured in the electric distributer, a band supporting the upper half of the ordinary ornamental shell, such band concentric with the gas-distributer and having holes therein through which the gas and electric bracket arms extend, whereby such band is supported by such arms, with non-electric conducting material interposed between the gas-arms and the band, and means for removably attaching the lower half of the ordinary ornamental shell to the electric distributer; substantially as described.

2. In a combined electric and gas fixture, the combination of a gas-distributer arranged to be secured to a gas-pipe, gas-pipe arms secured to the gas-distributer, an electric distributer surrounding the gas-distributer and attached thereto by the gas-arms extending therethrough, sleeves of non-electric conducting material on the gas-arms and a band supported by such sleeves, such electric distributer constructed of non-electric conducting material and metal plates secured thereto, such plates extending in horizontal planes above and below the non-electric conducting material and having lugs extending peripherally thereof, electric arms secured in such lugs, such electric distributer having holes through which the electric conductor of the fixture may be extended into the electric arms and to the lamps, and means for attaching the lower half of the globe of the fixture to the combined electric and gas distributer; substantially as described.

3. In a combined electric and gas fixture, a combined electric and gas distributer comprising a gas-distributer arranged to be secured to a gas-pipe, gas-pipe arms secured to the gas-distributer by extending thereinto, an electric distributer surrounding the gas-distributer and attached thereto by the gas-arms being extended therethrough, such electric distributer constructed of non-electric conducting material adjacent to the gas-distributer and to the gas-arms and metal rings

or plates secured to such non-electric conducting material, arms or brackets for supporting electric lamps secured to the electric distributer by being attached to the metal rings or plates on the non-electric conducting material, means for introducing an electric conductor through the combined electric and gas distributer into the electric-lamp-supporting arms, and means for removably attaching the lower portion of an ornamental globe to the fixture; substantially as described.

4. A combined electric and gas distributer comprising a gas-distributer, rings of non-electric conducting material surrounding the gas-distributer, such rings having grooves therein forming holes through which gas-arms can be inserted to be secured in the gas-distributer, metal plates, one of such plates having lugs extending peripherally of the rings, bolts extending through the metal plates and the rings and securing the plates and rings rigidly together, and a bracket secured to the electric distributer, in combination with gas-arms secured to the combined electric and gas distributer by being extended through holes in the electric distributer and into the gas-distributer, and electric arms secured to the combined electric and gas distributer by extending into the peripheral lugs; substantially as described.

5. The combination of a gas-distributer, rings of non-electric conducting material surrounding the gas-distributer, such rings having radial grooves on adjacent faces and additional grooves on the periphery alternating with the radial grooves, metal plates having lugs extending over the peripheral grooves of the rings, means for securing the rings and metal plates rigidly together, and means for securing the rings to the gas-distributer, and hollow electric arms secured in the projecting lugs over the peripheral grooves in the rings; substantially as described.

6. The combination of a gas-distributer, rings of non-electric conducting material surrounding the gas-distributer, such rings having radial grooves on adjacent faces and additional grooves on the periphery between the radial grooves, metal plates having lugs extending over the peripheral grooves of the rings, a bracket, bolts extending through the metal plates, the rings and the brackets rigidly securing them together, and hollow electric arms or brackets attached to the peripheral legs; substantially as described.

WILLY H. LAU.

In presence of—

CHARLES TURNER BROWN,
FLORA L. BROWN.
